UNITED STATES PATENT OFFICE.

REVERDY CLEMENT DE LA HUNT, OF CEDAR RAPIDS, IOWA.

DEODORIZING DEVICE.

SPECIFICATION forming part of Letters Patent No. 732,926, dated July 7, 1903.

Application filed October 26, 1901. Serial No. 80,068. (No model.)

To all whom it may concern:

Be it known that I, REVERDY CLEMENT DE LA HUNT, a citizen of the United States, residing at Cedar Rapids, in the county of Linn and State of Iowa, have invented certain new and useful Improvements in Deodorizing Devices; and I do hereby declare the following to be a full, clear, and exact description of the invention, such as will enable others skilled in the art to which it appertains to make and use the same.

My invention relates to water-closets, and has for its object to provide certain new and useful improvements in reference to the same.

15 A further and more specific object of my invention is to provide a simple and effective means for carrying off the stench from water-closet bowls.

20 A further object of my invention is to provide a means for carrying off the stench from water-closet bowls which may be attached and used to existing bowls and connections.

25 A further object of my invention is to provide a device for the above purposes which is simple in its operation, cheap to manufacture, and, above all, practical and efficient.

With all these objects in view my invention consists, broadly, in the application of an injector to water-closets.

30 My invention consists, further, in certain novel features of construction and in combination of parts, which will be first fully described, and afterward specifically pointed out in the appended claims.

35 Referring to the accompanying drawings, Figure 1 shows my invention in section. Fig. 2 is a sectional view of the aspirator to be used in connection with my invention. Fig. 3 is a sectional view of my valve.

40 I wish to state in connection with the foregoing figures, particularly Fig. 1, that the pipes and connections are shown in a manner which is best suited to illustrate my invention, but which in actual practice would be varied 45 to circumstances and arranged much more compactly with a view to economize space.

Like numerals of reference indicate the same parts throughout the several figures, in which—

50 1 is the bowl, constructed, preferably, as shown, having a discharge-chamber 2.

3 is the flush-tank, provided with the ordinary flush-pipe 4.

Connected to the discharge-chamber 2 are the discharge-pipe 5 and the vent-pipe 6, which are connected to the pipe 7.

8 is the water-pipe, which is connected to the pipe 9. At a point in said pipe is the valve 10, to which is secured the handle 11, the several parts of which valve will be hereinafter fully described. Below said valve 10 is an aspirator 12, which is connected to the flush-pipe 4 by means of a small pipe 13.

To return now to valve 10, it will be seen by referring to Fig. 3 that the same is of 65

simple construction. The valve-stem 14 extends to the exterior and is provided with suitable packing 15 to prevent leakage. The opposite side of the valve-chamber is pro-

vided with a removable plug 16, which must 70 be removed in order to furnish access to the valve. Said plug is provided with an opening in its inner face, which opening forms a

guide for the valve-stem 14. The valve is seated at 17 and arranged so that the pressure of water in pipe 8 tends to hold said valve 75 in a closed position. Pivoted to the exterior of the valve-chamber is a link 19, to which is

pivoted a handle 11, provided with an upwardly-projecting arm 18, to which is pivoted 80 the valve-stem 14. It is thus obvious that the weight of the handle 11 will hold the valve closed, although the pressure of water in pipe 8 is sufficient.

Referring now to Fig. 2, it will be seen that 85 the aspirator 12 is coupled to pipe 8, the bore of said aspirator decreasing from both ends toward the center, at which point this bore is

smallest. Directly opposite the central point and at right angles to the bore of the aspira- 90 tor is an opening 20, in front of which is

coupled a valve member 21, within which are a valve 22 and an air-chamber 23. Behind said valve is a small bore 24, which opens into pipe 13. Said valve is arranged so as to ex- 95

clude any passage of air or water from the aspirator into pipe 13, but allows a free passage of air from the opposite direction.

25 is the bowl-cover, which is connected to handle 11 by a suitable connecting-rod 26.

I also provide a small opening or openings 27 between the top of the bowl and the seat

28 for a purpose which will be hereinafter fully described.

Having thus fully set forth the several parts of my invention, its operation is as follows:

- 5 When in operation, the cover is raised, which raises the handle 11, thus opening the valve 10. This allows the water in pipe 8 to pass through pipe 9, valve 10, and aspirator 12, this causing a partial vacuum within air-
 10 chamber 23 in valve member 21, and sucks the vitiated air from the bowl 1 up into the flush-pipe 3, through pipe 13, into the air-chamber 23, where it is carried out into pipe 8 and down into vent-pipe 6, and thence to the discharge-pipe 5. The opening or openings 27 between the top of the bowl and the seat 28 allow fresh air to be taken into the bowl to replace the vitiated air which is carried off, thus causing a free current of air through the bowl as long as the aspirator is in operation.
 15 When the bowl is flushed and the seat lowered, the valve 10 is closed, which shuts off the supply of water through the aspirator, there being no further need for the same. I construct the pipe 9 so that after the valve 10 is closed the water in the pipe will form a trap at the bottom thereof, so as to prevent any vitiated or foul air from rising in said pipe 9 from the vent or discharge pipe.
 20 30 I do not wish to be understood as limiting myself to this specific construction, as the same may be varied in many ways and still fall within the limit and scope of my invention. I wish, furthermore, to state that the
 25 35 valve 10 may be operated manually, if desired, although I prefer to operate the same automatically, as described.

My invention may also be applied to urinals as well as water-closet bowls, as I have found the same to be particularly useful in connection therewith, and I therefore do not wish to be understood as limiting its application to water-closet bowls.

What I claim as new, and desire to secure by Letters Patent of the United States, is—

1. The combination with a water-closet bowl of a flush-pipe an aspirator connected thereto, a water-pipe carrying said aspirator, a valve in said water-pipe, a seat for said bowl, a cover for said seat, connecting means between said seat and said valve; and openings between said seat and bowl, substantially as described. 50

2. The combination with a water-closet bowl of a flush-pipe, an aspirator connected thereto, a water-pipe carrying said aspirator, a seat for said bowl, openings between said bowl and said seat, a cover for said seat adapted to operate said aspirator, substantially as described. 55

3. The combination with a water-closet bowl of a flush-pipe, an aspirator connected thereto, a seat, and a cover for said bowl adapted to operate the aspirator, and means for allowing a draft of air to pass through said bowl, when the same is in use, substantially as described. 60

4. The combination with a water-closet bowl, of a flush-pipe, a water-pipe, an aspirator connecting said flush-pipe and water-pipe, a valve in said water-pipe, a seat for said bowl, a cover for said seat, connecting means between said seat and said valve, and openings between said seat and bowl. 70

5. The combination with a water-closet bowl, of a flush-pipe, a water-pipe, an aspirator connecting said flush-pipe and said water-pipe, a valve in said water-pipe, a seat for said bowl, a cover for said bowl, connecting means between said cover and said valve and a valve in said aspirator, arranged whereby the water from said water-pipe is prevented from entering said flush-pipe from the aspirator. 75

In testimony whereof I affix my signature in presence of two witnesses.

REVERDY CLEMENT DE LA HUNT.
